TABLE LAMP BASE OR THE LIKE

Charles M. Wallace, 2407 Staples Ave., Key West, Fla.

Filed Aug. 7, 1958, Ser. No. 52,113

Term of patent 14 years

(Cl. D48—20)

Fig. 2.

Fig. 3.

Figure 1 is an elevational view of a table lamp base or the like showing my new design; and

Figure 2 is a reduced top plan view thereof.

Figure 3 is a reduced perspective view of the base member.

The dominant features of my design reside in the portions shown in full lines.

I claim:

The ornamental design for a table lamp base or the like, as shown and described.
